UNITED STATES PATENT OFFICE.

JOHN K. OLSEN, OF CHICAGO, ILLINOIS, ASSIGNOR TO STEWART-WARNER SPEEDOMETER CORPORATION, OF CHICAGO, ILLINOIS, A CORPORATION OF VIRGINIA.

ODOMETER.

Application filed February 1, 1922. Serial No. 533,175.

To all whom it may concern:

Be it known that I, JOHN K. OLSEN, a citizen of the United States, residing in the city of Chicago, in the county of Cook and State of Illinois, have invented certain new and useful Improvements in Odometers, of which the following is a specification, reference being had to the accompanying drawings, forming a part thereof.

10 The purpose of this invention is to provide an improved construction of a counter train, particularly of the type of an odometer, having the counter wheels graduated in terms of distance of travel of a vehicle to be served by the instrument, which shall be simpler and more compact in construction than similar devices heretofore employed. It consists in the elements and features of construction shown and described, as indicated in the claims.

In the drawings:

Figure 1 is a direct front elevation of an odometer embodying this invention.

15 Figure 2 is a section at the line, 2—2, on Figure 1.

Figure 3 is a section at the line, 3—3, on Figure 2.

Figure 4 is a section at the line, 4—4, on Figure 3.

20 Figure 5 is a section at the line, 5—5, on Figure 3.

Figures 6 and 7 are side elevations of two slightly differing wheels of the speed reducing train.

25 In the structure shown in the drawings there is a frame or support, A, comprising end bearings, A¹ and A², in which there is mounted for rotation and limited longitudinal movement a main central shaft, B, for

30 which the journal bearing is provided in the left-hand standard, A¹, by means of an intruded bushing, a¹, adapted, by being screwed in, to be adjusted within a limited range and secured as adjusted by a nut, a¹⁰.

35 The end of the shaft which is journaled in this bushing is axially bored at b for the housing of a spring, F, which reacts between the shaft and the bushing for yieldingly holding the shaft thrust to the right to a

40 limit which is determined by the encounter with the bushing, a², of the shoulder, b⁵, formed on the shaft toward the right-hand end by reduction in diameter at the right-hand-end portion, as shown at B¹. On the

45 shaft, B, there is mounted loosely a drive

gear, C, adapted to be driven in any suitable manner by or from the shaft whose revolutions are to be counted or indicated; and one purpose of this invention is to adapt the instrument for direct driving of this gear 60 by the intruded drive shaft, M, journaled in the frame, A, and having a worm, M¹, engaged directly with the gear, C, as stated. On the shaft, B, at the right hand side of the drive gear, C, there are mounted the numeral wheels or dials, D¹, D² and D³, of the odometer trip train, graduated as usual, 65 decadimally, the initial right hand dial being graduated to indicate tenths of miles, the next numeral wheel being the units wheel, 70 and the third at the left being tens wheel. Between said tens wheel, D³, and the drive gear, C, there is disposed a disk spring, K, for taking up the slack of the trains of dial 75 wheels on the shaft, and holding the several 75 members thereof in snug relation to each other. At the left hand side of the gear, C, there are shown in succession, three wheels, e¹, e² and E, which together with carrying 80 pinions, G, on the countershaft, g, parallel 80 to the shaft, B, constitute the speed-reducing train from the gear, C, to the lowest graduated dial wheel of the total travel train which comprises the dial wheels, E², E³, E⁴, E⁵, and E⁶. This speed-reducing train is cal- 85 culated to give to the wheel, E, the same ro- 85 tative speed as the wheel, D¹, of the trip train, and the reduction from that point in being by decimals, the wheel, E², of the total 90 travel train corresponding to the wheel, D², 90 of the trip train. In the particular con- 90 struction shown in the drawing, the speed 95 reduction from the gear, C, to the dial wheel, E², is 500 to 1, and to obtain this speed 100 change in three steps, one of the steps is nec- 100 essarily reduction from 5 to 1, which is ef- 105 fected by making the mutilated gear concerned in this particular step with two tooth 105 engagements, 180 degrees apart, as seen in Figure 7, while the others have only one such tooth engagement as seen in Figure 6. The initial or lowest-denomination wheel, 110 D¹, of the trip train is engaged with the shaft, B, for rotation by means of spline or inwardly-projecting pin, d¹⁰, on the wheel 110 engaging a longitudinal groove, b¹⁰, in the shaft, as seen in Figure 3. Similarly, the corresponding wheel, E, of the total travel train is engaged with said shaft, B, by an inwardly-projecting pin, e, on the wheel en-

gaging any one of ten longitudinal grooves, b^{10} , on the shaft, as seen in Figure 3. In addition to the longitudinal or paraxial grooves, b^{40} , there is provided a circumferential groove, b^{50} , in the shaft, as seen in Figure 3, positioned offset from the plane of rotation of the spline or pin, e , at the normal position of the shaft, B, a distance equal to the thrust of the shaft from its normal position to the limit determined by the clearance provided by the depth of the bore in the journal bushing, a^1 , so that when the shaft is thrust in to that limit, the spline or pin, e , being in the groove, b^{50} , the shaft 10 rotates without rotating the numeral wheel, E, and therefore, of course, without operating any of the remainder of the total travel train.

Because the wheels, e^1 , e^2 and E, are in 20 the same mechanical relation to the structure as the dial wheels of the total travel train, and might be graduated, if it were desired, to indicate travel, but are not so graduated, I have termed these wheels 25 "dummy" or numeral-less dials; and because the wheel, E, has the same speed of rotation as the lowest denomination wheel, D^1 , of the trip train, I find it convenient to refer to this wheel, E, as the "lowest-denomination 30 wheel" of the total travel train, although it is not graduated. The dummy wheels, e^1 and e^2 , are both loose on the shaft, and the wheel, e^1 , is rigid for rotation with the drive wheel; and, as indicated above, 35 these wheels, e^1 , e^2 and E, together with the carrying means connecting them successively, constitute the speed-reducing train by which the speed derived by the wheel, E, from the drive wheel, C, is reduced to one-fiftieth of 40 that of said drive wheel.

The right-hand end of the shaft, B, is 45 provided with an operating knob, B^4 . The operation of the structure described will be understood to be, that in the ordinary operation,—that is, when driven by a wheel or shaft whose speed is to be indicated,—rotary motion is first communicated through said gear wheels, e^1 and e^2 , and their respective carrying means to the wheel, E, which by 50 the spline-and-groove engagement described, rotates the shaft, B. Said shaft, B, in turn by the spline-and-groove engagement described, rotates the lowest-denomination wheel D^1 of the trip train; and from said 55 wheels, E and D^1 , respectively, proper rotation is to be made by the carrying devices to the successive wheels of the trip train and total travel train, respectively.

For resetting, the operator will push 60 inward on the knob, B^4 , thrusting the shaft, B, to the inward limit, causing the disengagement of said shaft from the gear, E, but not affecting the engagement of the shaft with the gear, D^1 . While the shaft is thus 65 thrust inward, it may be rotated in either

direction for setting the trip train either forward or backward to any desired point, without affecting the total travel train. For holding the shaft at the in-thrust position described, and also for preventing it from being too easily thrust in by accidental impact with the knob, the shaft has two grooves, b^6 and b^7 , just back of the stop shoulder, b^5 ; and there is provided a spring loop, S, which is sprung onto the shaft and 70 into one of the grooves, b^6 , before the bushing, a^2 , is screwed into the bearing standard; and said bushing when screwed in confines the spring loop, S, in the bearing, preventing 75 any movement of the loop longitudinally of the shaft. When the shaft is pushed inward the spring loop snaps over from the groove, b^6 , in the groove, b^7 , and engages the latter groove deeply and strongly enough 80 to prevent disengagement by the reacting thrust of the spring, S, but permitting the shaft to be readily pulled out again, snapping the spring over into the groove.

It will be observed that by reason of the fact that the total assemblage of wheels on the shaft fully occupies the space between the bearing members afforded by the standards, A^1 and A^2 , and the bushings therein, except as to the accommodation which is taken care of by the spring, K, the longitudinal movement of the shaft, B, for resetting the trip train will have no tendency to displace the gear C, out of engagement with the driving worm of the inleading shaft, so long as the spring, K, is stiff enough to overcome the slight frictional engagement of the gear, C, with the shaft. And this is found to be adequate means for insuring the undisturbed engagement of the gear, C, with 90 its driving means.

I claim:—

1. In a resetting device for a revolution counter in combination with a frame structure, a main central shaft supported in said frame; two decimal series of counter wheels on said shaft, the several wheels of each series being side by side on the shaft; a driven gear on said shaft, and driving connections from said gear to said shaft and also to the lowest denomination wheel of one of the series of counter wheels, the lowest denomination wheel of the other series being engaged with said shaft for rotation thereby, both of said shaft engagements being sliding, the first adapted for disengagement upon a predetermined sliding movement of the shaft and the second adapted for continuous engagement throughout the sliding movement, and means for preventing lateral displacement of the counter wheels in said longitudinal movement of the shaft; whereby such longitudinal movement of the shaft disconnects it as to rotation both from the driven shaft and from the first mentioned series of counter wheels 100

105

110

115

120

without disengagement from the second series.

2. In combination with a frame structure a main central and integral shaft, supported in said frame; two decimal series of counter wheels on said shaft, the wheels of each series being side by side thereon and the lowest denomination wheel of one series being engaged with said shaft for rotation thereby, a driven gear on said shaft; and driving connections from said gear to said shaft and also with the lowest denomination wheel of one of said series, both said engagements of said shaft being adapted to permit longitudinal movement of the shaft, the second mentioned engagement being adapted for disengagement by such longi-

tudinal movement to a predetermined limit the other of said engagements being continuous throughout such movement, means 20 for preventing lateral displacement of the counter wheels by longitudinal movement of the shaft.

3. In the construction defined in claim 1 foregoing, the driving connection between 25 the gear and the lowest denomination counter wheel mentioned being disengageable by the longitudinal movement of said integral shaft.

In testimony whereof, I have hereunto set 30 my hand at Chicago, Illinois, this 28 day of Jan. 1922.

JOHN K. OLSEN.
